UNITED STATES PATENT OFFICE.

ROBERT F. WHITNEY, OF WINCHESTER, MASSACHUSETTS.

HIDE-WORKING MACHINE.

1,075,887.

Specification of Letters Patent.

Patented Oct. 14, 1913.

Application filed April 29, 1910. Serial No. 558,461.

To all whom it may concern:

Be it known that I, ROBERT F. WHITNEY, a citizen of the United States, and resident of Winchester, in the county of Middlesex and State of Massachusetts, have invented certain new and useful Improvements in Hide-Working Machines, of which the following is a specification.

This invention relates to that class of machines for fleshing, unhairing and working hides and leather, in which the hide is plated over a movable bed roll, by which it is carried into contact with the work roll and supported while being treated by said work roll; and its object is to provide an additional bed table, or tables, so that the work roll may simultaneously operate upon different parts of the hide; all being so arranged that ample room is provided for introducing the hide into the machine.

The invention is illustrated by the accompanying drawings in which—

Figure 1 is a side elevation of the machine looking from the left of Fig. 2. Fig. 2 is a front elevation of the machine. Fig. 3 is a detailed view of the table and its connections. Fig. 4 is a modification of Fig. 3 showing a plurality of tables.

Similar characters refer to similar parts throughout the several drawings.

The main frame of the machine consists of side frames 1 connected by tie girts 2. Work roll 3 is mounted on shaft 4 journaled in the frame. Bed roll 5 is mounted on shaft 6 journaled in swinging arms 7 fulcrumed on studs 8 fixed to the frame. Feed roll 9 is mounted on shaft 10 journaled in swinging boxes 11 fulcrumed on studs 12 fixed to the frame and pivoted at 13 to spring-controlled rods 14 slidably mounted in the frame. Table 15 is fixed to swinging arms 16 fulcrumed on shaft 6 of bed roll 5. Rollers 17 are mounted in longitudinally adjustable swinging arms comprising upper members 18 slidably engaging lower members 19 and furnished with springs 20 which act as cushions for said rollers 17; said members 19 being fulcrumed on studs 8. This table 15 may be made of any desired form and material, but is preferably made of cast iron and in the form of a box which is furnished interiorly with a series of transverse springs 15^b, which form a cushion for the top of said box which preferably consists of a yielding covering, such as leather or rubber.

In Fig. 4 is shown a modification of the machine embodying a plurality of tables, namely, table 15^a fixed to the swinging arms 16^a and table 33 pivoted at 33^a to said swinging arms 16^a and resting on the studs 33^b mounted longitudinally adjustably on said swinging arms 16^a. Eccentrics 7^a, mounted on shaft 21, are pivoted to toggles 22 whose inner links are pivoted at 23 to swinging arms 6^a 7 and whose outer links are pivoted at 24 to rockers 25 pivoted at 26 to the frame and at 27^a to spring-controlled rods 27 slidably mounted in the frame. Eccentrics 19^a, mounted on shaft 21, engage and operate 70 swinging arms 18—19. Shaft 21 is mounted in the frame and furnished with a gear 28 through which it is rotated by clutch 29 mounted on shaft 29^a fixed in the frame, the driving member of which clutch is furnished 75 with gear 29^b through which and intermediate gearing it is actuated by pulley 30. The clutch is operated by treadle 31 mounted on shaft 21 and connected with the clutch mechanism by chain 31^a. The work roll is 80 operated by pulley 32 fixed to its shaft. The clutch mechanism employed to rotate shaft 21 and the gears employed to rotate the bed roll are shown but need not be described as they form no part of the present 85 invention, which lies entirely in the combination of the work roll with the table, or tables, and bed roll, described, irrespective of the means employed for bringing these parts together and separating them. 90

The operation is as follows: Normally, when inoperative, the table 15 and bed roll 5 are in the position shown in dotted lines Fig. 3, providing ample room for the insertion of the hide; the work roll 3 is being 95 driven through pulley 32; the feed roll 9 is at rest; and the driving member of the clutch is being driven through the pulley 30. After inserting the hide, the operator depresses treadle 31, thereby engaging the 100 clutch members, actuating the eccentrics and bringing the operating parts together as shown in full lines Fig. 3. When the rolls are together, bed roll 5 is rotated by the gearing shown, but not described, and feed 105 roll 9 is rotated frictionally. As soon as the operating parts are brought together, the clutch members become automatically disengaged, leaving the operating parts together, until the operator again depresses 110 the treadle, when the clutch operates to separate the operating parts and thereupon

again becomes automatically disengaged. The operation is similar when a plurality of tables is employed, as shown in Fig. 4.

By the improvement described, work is done upon the hide or leather along the lines where it passes between the work roll and the table, or tables, and where it passes between the work roll and the bed roll, and this is the principal feature of my invention; but, as will be readily seen, by this arrangement a portion of the hide or leather is held tightly wrapped around that part of the work roll which extends between said contacts with the table, or tables, and bed roll, so that effective work is also done on that portion of the hide. The machine is particularly adapted to unhairing and working out different hides and skins and also to putting out or setting leather in the different stages of manufacture.

Having described my invention what I claim and desire to secure by Letters Patent is:

1. In a machine of the character described, in combination, a work roll; a bed roll having a shaft journaled in swinging arms; and a table fixed to swinging arms fulcrumed on said bed roll shaft; said bed roll and said table being movable into and out of contact with said work roll; with means for accomplishing said movements; substantially as described.

2. In a machine of the character described, in combination, a work roll; a bed roll having a shaft journaled in swinging arms; and

a plurality of tables mounted on swinging arms fulcrumed on said bed roll shaft; said bed roll and said tables being movable into and out of contact with said work roll; with means for accomplishing said movements; substantially as described.

3. In a machine of the character described, in combination, a work roll, a bed roll and a table; said bed roll and said table being simultaneously movable into and out of contact with said work roll; with means for accomplishing said movements; substantially as described.

4. In a machine of the character described, in combination, a work roll, a bed roll and a plurality of tables; said bed roll and said tables being simultaneously movable into and out of contact with said work roll; with means for accomplishing said movements; substantially as described.

5. In a machine of the character described, in combination, a work roll, a bed roll, a table and a feed roll; said table being movable into and out of contact with said work roll; said bed roll being movable into and out of contact with said work roll and said feed roll; with means for accomplishing said movements; substantially as described.

In testimony whereof I have affixed my signature, in presence of two witnesses.

ROBERT F. WHITNEY.
